WINDOW WASHING DEVICE

Anthony C. Ruggiero, Brooklyn, N. Y.

Application December 21, 1946, Serial No. 717,704

1 Claim. (Cl. 15—232)

1

This invention relates to window washing devices in general.

Among the objects of the present invention it is aimed to provide an improved window washing device, particularly suited for washing the outer rear faces of slideable window sashes, with which device the window cleaner is not required to face the window when cleaning the outer side thereof.

Particularly with vertically slideable window sashes, as extensively used in the tall buildings of New York city, it has been the convention for window cleaners employed to clean such windows, when required to clean the outer faces of the windows, to step on the window sill and either before or after starting the cleaning operation to fasten themselves to the outer sides of the building by safety belts and the like. While this convention may be practicable for so-called professional window cleaners, the average housemaid who is required to clean the outer faces of windows in tall buildings, hotels, apartment houses and the like, gains access to the outer faces by devious awkward ways so hazardous that many, if not most housemaids, refuse to take positions which require such duties. With this hazard in mind, the present invention aims to provide an apparatus which can with facility be manipulated either by a man or woman while the operator is standing, or in some cases even sitting, within the building, that is, while he or she is located on the inside of the window being cleaned.

More specifically, the invention contemplates the use of an apparatus having a pivotally mounted head to which may be expeditiously secured either wet or dry cleaning cloths, chamois sheets or the like, and an arrangement of levers which can be quickly secured in different configurations according to the portion of the window to be cleaned.

These and other features, capabilities and advantages of the present invention will appear from the subjoined detail description of specific embodiments thereof illustrated in the accompanying drawings, in which

Fig. 1 is a perspective of a slideable window and of the apparatus constituting the present invention in position for use.

Fig. 2 is an enlarged side elevation of the apparatus.

Fig. 3 is a section still further enlarged on the line 3—3 of Fig. 2.

In the embodiment shown, there is illustrated a conventional window frame 1 having two vertically slideable window sashes 2 and 3. The apparatus consists essentially of the detachable han-

2

idle bars 4 and 5 forming a J-shape or quasi J-shape as shown secured to one another and to the bent arm or rod 6 which has hingedly connected thereto the outer arm or rod 7, which in turn is pivotally connected to the bifurcated bracket 8 secured to the rod or arm 9 which is pivotally connected to the block or bracket 10 slidably mounted on the arm or rod portion 11 of the bent arm 6. The block 10 is yieldable relative to the arm 11 and is provided with a tie-screw or set screw 12 and nut 13 for deflecting the walls of the block 10 to frictionally engage the arm 11 against movement when desired.

The free end of the rod 7 is pivotally connected to a head 19. The head 19 is provided with any suitable fastening means for attaching thereto cleaning material such as a wet or dry cloth, chamois sheet, or the like.

When the upper part of the window, such as the inner window 2 in the upper position is to be cleaned, then, as shown in Fig. 1, the bracket 10 is so fastened on the arm 11 that a decidedly large obtuse angle is formed between the arms 7 and 6. When the lower part of the inner window 2, moved into the lower position, is to be cleaned, then the bracket 10 is so fastened on the arm 11 that a decidedly small acute angle is formed between the arms 6 and 7, and at least the handle portion 4 removed, if not both handle portions 4 and 5 removed, and either the handle portion 5 alone engaged or the handle portion 5 and the arm 6 engaged or the arm 6 alone engaged by the operator when manipulating the apparatus.

The block 10 preferably has slots 32 cut therein at opposite ends of the opening 34 provided for receiving the arm portion 11, and consequently when the arm portion 11 is positioned in the opening 34, and the nut 13 is tightened on the screw 12, the opposite walls of the block 10 will then be deflected frictionally to grip the arm portion 11. Preferably as shown, the arm 9 is provided with an enlarged portion 35, which is journaled on the smooth shank portion of the screw 12.

The arms 6 and 7 are movable relative to one another being connected at their ends to the hinge 36.

Any suitable anchoring means for connecting the cloth to the head 19 may be provided so long as this anchoring means will firmly anchor the cloth in place while being used and so long as this anchoring means can be quickly and expeditiously operated both for anchoring a cloth, for removing a cloth and again anchoring a second cloth.

It is obvious that various changes and modifications may be made to the details of construction without departing from the general spirit of the invention as set forth in the appended claim.

I claim:

The combination of a support for a window cleaning material parallel to and engaging the outer face of the window to be cleaned, a first straight supporting arm pivotally connected to said support and extending at an oblique angle 10 to the face of the window to be cleaned, a second supporting arm pivotally connected to said first supporting arm and having a bend therein, a bracing arm pivotally connected at one end to said first supporting arm intermediate the ends 15 thereof, a block slidably and permanently mounted on said second supporting arm between said bend and the outer free end thereof and pivotally connected to the other end of said bracing arm, the bend forming a stop to determine the outermost position of the block, and a set screw for frictionally anchoring said block against movement at a predetermined angle of said supporting arms to one another, the free end of said second arm 20 extending to and beyond the inner face of the 25

window to be cleaned to enable operation of the combination from a point inwardly of the window to be cleaned.
